UNITED STATES PATENT OFFICE.

LESLIE A. VANDIVER, OF KANSAS CITY, MISSOURI.

HOLDER.

Application filed May 10, 1922. Serial No. 559,843.

To all whom it may concern:

Be it known that I, LESLIE A. VANDIVER, a citizen of the United States, residing at Kansas City, in the county of Jackson and State of Missouri, have invented a new and useful Holder, of which the following is a specification.

By way of explanation it may be stated that it is the common practice in dentistry, 10 to anchor or secure the dam externally, the result being that a considerable amount of dam is used and wasted, a further result being that the patient not infrequently is subjected certainly to inconvenience and 15 discomfort, and often to pain, by the means for holding the dam in place.

The foregoing being understood, it may be stated that this invention aims to provide a simple means whereby the dam may be held, 20 for the most part, or entirely within the mouth of the patient, a minimum amount of dam being used, and the patient being subjected to none of the inconvenience or pain which results from anchoring the dam 25 externally.

Another object of the invention is to provide a dental dam having a reflecting surface, to the end that the operator may be afforded added light.

30 It is within the province of the disclosure to improve generally and to enhance the utility of devices of that type to which the invention appertains.

With the above and other objects in view, 35 which will appear as the description proceeds, the invention resides in the combination and arrangement of parts and in the details of construction hereinafter described and claimed, it being understood that, within 40 the scope of what is claimed, changes in the precise embodiment of the invention shown can be made without departing from the spirit of the invention.

In the drawings:—

45 Figure 1 shows in vertical section, one form of device constructed in accordance with the invention, the same being located in the mouth of the patient; Figure 2 is an elevation of the structure shown in Figure 50 1, out of the mouth of the patient; Figure 3 is a fragmental plan showing a slight modification; Figure 4 is a plan showing a modified form of the invention; Figure 5 is a section on the line 5—5 of Figure 4; and 55 Figure 6 is a section on the line 6—6 of Figure 4.

In carrying out the invention as contemplated in Figures 1 and 2, there is provided a frame, denoted generally by the numeral 1, and ordinarily in the form of a plate, 60 fashioned from metal or any other suitable substance having the necessary rigidity. The frame 1 includes an intermediate body 2 and forwardly extended wings 3 at the opposite ends of the body, the wings preferably being disposed at an obtuse angle to the body. In the body 2 and in the wings 3, arcuate openings 4 are formed. Tongues 5 and 6 are fashioned integrally with the body 2, and project in opposite directions 65 into the openings 4, the tongues being disposed at an acute angle to the body and being inclined in a direction opposite to that in which the wings 3 extend. At their ends and at their sides, the wings 3 are provided with apertured lugs 7 shown most clearly in Figure 3, although Figure 3 discloses a modification having nothing to do with the lugs.

The rubber dam 8 is placed behind the 80 body 2 and is carried forwardly along the wings 3, the dam being punched, so that the lugs 7 may extend therethrough, the dam being folded backwardly upon the wings 3, as shown at 9. Clamps 10 are slipped over 85 the ends of the wings, to aid in holding the dam, the clamps having openings 11 receiving the end portions of the wings.

In Figure 2, the clamps 10 are shown as separable. In Figure 3, parts hereinbefore described have been designated by numerals previously used, with the suffix "a". In this form of the invention, the clamps 10a are pivoted at 12 to the wings 3a.

The dam 8 is punched to receive the teeth 95 14, or the tooth, to be filled. The frame 1 is located partly in the mouth of the patient, the wings 3 projecting outwardly, as shown in Figure 1, the openings 4 serving to receive the upper and lower teeth, and the 100 tongues 5 and 6, the tongue 5 in the application shown in Figure 1 serving to stretch the dam to the arch of the mouth.

The construction of the device, obviously, is such that ordinary anchoring means for 105 the dam may be dispensed with. The frame 1, when in the position shown in Figure 1, serves as a jaw rest for the patient.

Especial attention is directed to the fact that the dam 8 is covered with a light reflecting substance, such as aluminum, which 110 aids the operator in his work.

The device as above described is adapted to be used for anterior teeth, but when posterior teeth are to be filled, recourse may be had to the structure shown in Figures 4, 5 and 6, wherein there is disclosed a frame 15, which may be of rectangular outline, the frame having lugs or prongs 16. The frame is provided at its ends with bosses 17, facilitating the handling of the frame. **U**-shaped clamps 18 are pivoted at 19 to the frame 15 and may be provided with openings 20 for the reception of the lugs or prongs 16. The dam 21 is placed across and folded upon the frame 15 and is held thereon by the prongs 16 and by the clamps 18. The dam 21 is punched for the reception of the tooth 22, the dam being held about the tooth by an ordinary clamp 23 which is not described in detail because it is a standard article of manufacture, the construction and operation of which is well understood by dentists. The tooth 22 projects through the opening 24 in the frame 15, and through the dam 21, as shown in Figure 5, the cavity in the tooth, which is to be filled, obviously being kept in a dry condition. The dam 21 has a reflecting surface, as hereinbefore described.

What is claimed is:—

1. In a device of the class described, a frame comprising a body having wings, and provided with openings adjacent the base of said wings, the frame having a dam stretching tongues cooperating with the openings. 30
2. In a device of the class described, a frame including a body having forwardly presented wings at the upper and lower ends thereof, the body having a tooth receiving opening adjacent each wing, and dam holding means on the frame. 35
3. In a device of the class described, a frame comprising a body provided with forwardly presented wings, the frame having tooth-receiving openings extended into the wings, and being provided with rearwardly inclined dam-stretching tongues, cooperating with the openings; and dam-holding means carried by the frame. 40

In testimony that I claim the foregoing as my own, I have hereto affixed my signature in the presence of two witnesses. 50

LESLIE A. VANDIVER.
